UNITED STATES PATENT OFFICE.

HANS HARTMAN, OF NEW YORK, N. Y., ASSIGNOR TO SUBMARINE EXPLORATION CO.
INC., A CORPORATION OF NEW YORK.

APPARATUS FOR TAKING SUBMARINE MOTION-PICTURES.

1,250,582.

Specification of Letters Patent. Patented Dec. 18, 1917.

Application filed November 6, 1915. Serial No. 59,948.

To all whom it may concern:

Be it known that I, HANS HARTMAN, a citizen of Austria-Hungary, residing at New York, in the county of New York and State of New York, have invented certain new and useful Improvements in Apparatus for Taking Submarine Motion - Pictures, of which the following as a specification.

This invention relates to an apparatus for taking submarine photographs and has for its main object, the provision of an automatic photographic device for taking submarine pictures or a series of photographs at any desired depth of water.

More specifically, the invention is constructed with a view to providing a novel, efficient and more desirable type of apparatus of this nature; one in which the photographs are taken always at the desired illuminated area since the camera is mounted at an angle to the line of projection of light; a construction wherein the means for taking the photographs may be mounted and adjusted at any preferred angle, and a construction having efficient stabilizing means in the nature of a gyroscope.

With the above and additional objects, such as will hereinafter appear, in view, the invention has been embodied in one preferred form as illustrated in accompanying drawings wherein:—

Figure 1 is a side elevation of the apparatus;

Fig. 2 is a view in front elevation of the apparatus;

Fig. 3 is an enlarged vertical sectional view through the commutator and associated parts to impart rotary motion to the picture-taking means;

Fig. 4 is an enlarged vertical sectional view of the lower part of the apparatus, particularly showing the buffer, the gyroscope and pivotal connection of the structure mounting said parts to the frame;

Fig. 5 is a detail end view of the winding means of the searchlight-adjusting means; and

Fig. 6 is a diagrammatic view showing the electrical connection of the parts.

Referring specifically to the drawings, wherein like reference characters designate like or corresponding parts in the different figures, the device is suspended from a strong cable 1 through which pass and in

wires 2 (see Fig. 3). A casing is provided of which 3 is a container and 4 a top removably secured to the container by means of bolts 5. Numeral 6 designates an electric motor which has an upwardly extending hollow shaft 7 on which is secured, within the container 3, a crown bearing 8. Container 3 has an inwardly extending annular flange 9 which is overlapped by the bearing 8 and between which flange and bearing 65 suitable bearing balls 10, to reduce friction, are disposed. Crown bearing 8 supports the motor 6 and the picture taking means (later to be described) for rotation independently of casing 3—4.

The conductors 2 lead to the interior of container 3 and are fastened to suitable binders 11 insulated at 12 from the container. From the binding conductors 11, extend brushes 13 which wipe the periphery 75 of conducting rings 14 which turn with a shaft 15 of motor 6. Conductor wires 16 embedded longitudinally of shaft 15 contact with the rings 14 and serve to feed the electric current from the rings 14 to other elements of the apparatus.

It may be mentioned that the apparatus is waterproof at the connection of elements 3 and 4 and insulated from the water by an insulating sheet 17 and by means of an insulating annulus 18, shaft 7 and bearing 8 are insulated from and rendered waterproof at their junction with container 3 at flange 9.

Suspended from the motor 6 and so as 90 to rotate therewith, is a frame 19 to which a powerful electrically illuminated searchlight 20, of a waterproof construction, is pivoted by trunnions at 21. Fastened to the top of the searchlight 20 is a photographic camera 22 which is continuously driven by an electric motor 23 after the apparatus has been lowered into the water and the current supplied. By reason of the fact that the camera is disposed at an angle to 95 the line of the rays of light or the horizontal center of the searchlight, the pictures will always be taken through the illuminated area at the best illuminated location.

Mounted in a suitable bracket 24 fastened 105 to the rear of the searchlight 20, is a turnable drum 25 about which may be wound one terminal end of a flexible wire or cord 26, the other terminal end of which is fastened to a lug 27 secured to the exterior of 110

motor 6. The drum is turned by means of a handle 28 fastened to the shaft 29 of the drum. On shaft 29 a ratchet wheel 30 is fixed which is engaged by a pivoted pawl 31 urged by a leaf spring 32. Through the turning of handle 28 and of the drum, the element 26 is wound about the drum or paid out and as a result, the lamp 20 and camera are shifted as an integer to a desired angle. Since the pawl 31 automatically snaps into engagement with ratchet wheel 30, the drum is prevented from displacement out of an adjusted position.

At the lowermost point of frame 19, a suitable socket 33 is secured which mounts a ball 34 in order to pivotally connect a gyroscope casing from the frame. This frame comprises a cover 35 with which the ball 34 is formed integrally and a container 36 removably secured to the cover 35 by means of bolts 37. An insulating and waterproofing packing ring 38 is provided at the junction of the top cover 35 and container 36. Within the casing 35-36, a suitable stabilizing means is mounted, preferably the gyroscopic device now to be described. The feed wires connect to conducting binding posts 39, preferably insulated from the cover 35 at 40. Brushes 41 conduct the current to a commutator 42 with which is associated an armature 43 and electro-magnets 44. This construction is, in effect, an electric motor which rotates a shaft 45 with which turns a large stabilizing fly-wheel 46. Fly-wheel 46 is provided with a bearing 47 extending into a recess of container 36 and turning on balls 48 in order to reduce friction between the parts.

Suitable means is employed to minimize the danger of injury to the apparatus upon the same striking an obstacle. To this end, I may form a tube 49 of any suitable length, integral with the container 36 and to depend therefrom. Slidably vertically within the tube 49, is a buffer 50. A compression spring 51 is disclosed within the said tube and so as to normally maintain the buffer projected. In Fig. 4, the buffer is but partly projected which is the position it would assume upon receiving a moderate shock. Grooves 52 may be provided in buffer 50 to receive the inner ends of guide and mounting pins 53.

By reference to Fig. 6, it will be noted that the current is fed from any suitable source by the wires 2 to the commutator of motor 6. Conductors 2 are then continued, having branch wires 54 to energize motor 6; branch wires 55 to energize the motor 23 of camera 22; branch wires 56 associated with the searchlight 20, and the wires having their terminals connected to the gyroscope motor at 39.

In operation, the device is lowered to any desired depth into the water from a vessel or other supporting means, suspended

through the medium of the strong cable 1. At the preferred time, after lowering of the apparatus, the electric circuit is closed whereupon the current will flow through the apparatus and simultaneously operate the commutator of motor 6, the motor 6, motor 23 and thereby the camera 22; render the searchlight 20 highly luminous and operate the gyroscope and especially the stabilizing fly-wheel 46. It will be realized that the stabilizer 46 will keep the turning parts of the apparatus sufficiently stable for effective photographing purposes. It may be that cable 1 will tend to turn with the parts from motor 6 and therefore a plurality of vanes 57 are preferably fastened to the container 3 so as to retard turning movement of the cable and casing 3-4. Shocks are absorbed by the buffer 50 should the apparatus encounter an obstruction during the lowering action.

It is to be understood that changes in the details of construction may be resorted to provided they fall within the spirit and scope of the appended claims.

I claim:

1. In a device of the class described, the combination of a frame, an electric light projector pivotally mounted within said frame, means to adjust said light projector to different angles independently of the vertical position of the frame and the photographic means mounted upon said light projector, and disposed at an angle to the same.

2. In a device of the class described, the combination of a frame, a light projector pivotally mounted within the frame, means to adjust said light projector to different angles within the frame, photographic means mounted upon said light projector and disposed at an angle to the same and means to turn said frame on its vertical axis.

3. In a device of the class described, the combination of a frame, a light projector pivotally mounted within said frame, means to adjust the light projector to different angles within the frame, photographic means mounted upon said light projector and disposed at an angle to same, means to turn said frame on a vertical axis and resistance means to prevent the cable on which the device is suspended from following the frame in turning movement.

4. In a device of the class described, the combination of a suspended frame, a light projector pivotally mounted within said frame, means to adjust the light projector to different angles within the frame, photographic means disposed at an angle to the light projector, means to turn the frame on its vertical axis and shock absorbing means attached to and adjacent to the base of the device.

5. In a submarine camera of the class de-

scribed, the combination of a suspended frame, a light projector pivotally mounted within said frame, means to adjust the light projector to different angles, photographic means disposed at an angle to the light projector, a water tight casing supported from the frame, a gyroscope device within said casing operable to stabilize the frame in the water, a depending tube at the lower-
most part of the casing, a buffer slidable 10 within said tube, and cushioning means for said buffer within the tube.

In testimony whereof I affix my signature in presence of two witnesses.

HANS HARTMAN.
